Steglitz, GermanyApplication March 18, 1937, Serial No. 131,689
In Germany March 28, 1936

2 Claims. (Cl. 250—27)

The invention relates to the production of deflecting voltages in Braun tubes by means of a relaxation oscillation generator. Instead of connecting the storage condenser of said generator directly to the deflecting plates it is advantageous to use an amplifier tube the grid of which is controlled by the generator and in the anode circuit of which feeds the primary of a step-up transformer the secondary of which is connected in push-pull to the deflecting plates. The relaxation device may accordingly be operated with low anode potentials of approximately 200 volts. The difficulty associated with the method consists in the fact that, when an ordinary triode or pentode having a high inner resistance is used for amplification, on the transformer appears not the curve of the storage condenser potential but about its time differential curve. It has accordingly been set forth in an earlier application Ser. No. 106,021 filed Oct. 16, 1936 that the relaxation voltage curve has to be integrated by charging a second condenser from the relaxation condenser before applying it to the grid, in order to obtain the correct deflection. In this method a disadvantage consists in the fact that the two condensers must be discharged simultaneously by way of a discharge tube having two anodes. It is the object of the invention to obtain the desired result on a simpler way which is based on the fundamental idea that on the secondary side of the transformer the correct linear relaxation curve appears if the transformer operates with a primary circuit having a very small internal resistance. The difficulty in putting this idea into practice resides in the fact that amplifying tubes, the internal resistance of which is small as compared to the primary input resistance of the transformer would require to be very large and uneconomical triodes. According to the invention, there is employed a normal triode provided with a small, adjustable anode resistance.

From the point of view of the transformer the inner working resistance of the tube is then equal to that of the parallel connection of tube and resistance 15, and consequently able to be reduced at desire by reducing the latter, of course with a certain loss of amplification.

The drawing shows an embodiment of the method. The battery 1 charges the storage condenser 3 in linear fashion by way of a resistance 2. For the purpose of discharge there may be employed a simple gas-filled triode 9. A resistance 17 for limiting the discharge current may be provided. By way of a blocking condenser 13

the relaxation voltage is applied to the grid of a triode 7, which is negatively biassed by way of resistance 14, and amplified in linear fashion. The internal resistance of 7, which resistance in itself is selected to be very small—tube with small amplification factor—is still further reduced in adjustable fashion by the parallel resistance 15 according to the invention. 15 is of the order of 1,000 to 5,000 ohms. The transformer 6 is coupled to the anode circuit by way of a large blocking condenser 16. The transformer is sufficiently well insulated between primary and secondary winding to prevent the high anode potential of the Braun tube from passing to earth. It is even possible by adjustment of 15 the resistance 15 to convert a convex-distorted deflection curve into a concave distorted one, and accordingly to obtain a linear one.

The transformer 6 must be capable of sufficiently transmitting the lowest frequency, i. e., 20 the relaxation frequency itself and some harmonics of it. For the image-change figure there may be employed a transformer which transmits between 50 and 3,000 periods; for the line change there is requested, corresponding to the number 25 of lines, a higher frequency band, for example in the case of a 200-line image a band of between 4,500 cycles and approximately 100 kilocycles.

In order to impose the relative smallness of 30 the inner resistance the impedance of the primary winding of 6 should be made as large as possible. There should accordingly be provided as many turns as possible on the transformer. This is simplified by the fact that, in accordance 35 with the invention, the direct current is blocked by the capacitative coupling 16. The wire, therefore of the secondary primary winding may be reduced in thickness to the smallest technical degree, i. e., in practice to approximately 40 0.01—0.07 mm.

Practical embodiment:

Transformation ratio=1:6,
Number of primary turns 4,500,
Amplifier factor of triode 7=10,
Internal resistance of 7=approximately 5,000
ohms,

Anode resistance 15=3,000 ohms,
Anode current approximately 10 milliamperes, 50
Voltage of battery 1=300 volts,
Transformation ratio of the potentials accomplished in practice approximately 1:4,
Potential between the plates approximately 700
volts.

I claim:

1. In an arrangement for the production of the deflecting voltages in a cathode ray tube having a pair of deflecting plates comprising a relaxation oscillation generator, an amplifying tube the grid of which is controlled by said generator and a step-up transformer the primary of which is connected to the output of said amplifying tube and the secondary of which is connected to the deflecting plates of the cathode ray tube, an adjustable resistance shunting the primary of said transformer, said resistance being small as compared to the reactance of said primary.
2. In an arrangement for the production of

15

the deflecting voltages in a cathode ray tube having a pair of deflecting plates comprising a relaxation oscillation generator, an amplifying tube the grid of which is controlled by said generator, and a large step-up transformer the primary of which is connected to the output of said amplifying tube and the secondary of which is connected to the deflecting plates of the cathode ray tube, an adjustable resistance shunting the primary of said transformer, said resistance being small as compared to the reactance of said primary, said amplifying tube being a triode of small amplification factor. 5 10
